ATTORNEY

UNITED STATES PATENT OFFICE

HARRY A. MARRABLE, OF LINOLEUMVILLE, NEW YORK

CLOTHESLINE

Application filed August 13, 1928. Serial No. 299,371.

Primarily this invention has reference to the provision of an endless clothes line of such construction and supported in such a manner that clothes may be hung on both 5 sides of the line and either of the sides or leads of the line may be pulled through the supporting pulleys therefor without the clothes pins which attach the articles on the line coming in contact with such pulleys and 10 whereby the line may be entirely filled with laundry and the usual annoyance of the operator awaiting the drying of laundry on one side of the line before hanging laundry on the other side of the line will be entirely 15 and effectively overcome.

The improvement while especially designed as a clothes line, is also susceptible to use in various other connections, as for instance, as a support for breeches buoys by life saving 20 workers which will permit a train of breeches buoys traveling from a wrecked ship to a point of rescue and another train of such buoys traveling from a point of rescue to the ship so that the work of rescue will be practically continuous, the improvement being 25 also susceptible for employment on cables employed for excavating, tunnelling, etc., as well as for use in connection with the seats attached to the chains or cables of water 30 merry-go-rounds at pleasure resorts, etc.

In the drawings:

Figure 1 is a perspective view of my improvement.

Figure 2 is a top plan view looking toward 35 one end of the improvement.

Figure 3 is a side elevation looking at rightangles to the showing of Figure 2.

Figure 4 is a sectional view approximately 40 on the line 4—4 of Figure 3.

Figure 5 is a side elevation illustrating a slight modification.

As disclosed by the drawings I make use of two oppositely disposed frames, each of which is of a similar construction and each of which 45 is substantially T-shaped in plan. Each frame is indicated by the numeral 1. Both the longitudinal and later branches of the frame are connected by plates 2, and pivotally secured in each of the frames approximately 50 in a line with the center of the outer and

longitudinal branch thereof, there is a grooved wheel 3.

By reference to Figures 3 and 4 of the drawings it will be noted that the pivot 4 for each of the grooved wheels 3 support the latter adjacent to the top of the frame, leaving a space between the pulley and the bottom of the frame. The lateral member of each frame 1 has swivelly connected thereto a hook 5 and these hooks are attached to suitable supports. 55

Around the pulleys there is trained an endless clothes line 6. The clothes line is braided or has otherwise attached thereto a lower or depending branch 7, the said branch 7 being connected and being of a less length than the clothes line proper. The branch 7 is connected at determined intervals by short ropes or like flexible elements 8 to one or both sides of the main or clothes line 6. The clothes are attached to the lower branch 7 of the clothes line, being attached thereto by the usual clothes pins. Either side or lead of the clothes line 6 may be pulled longitudinally to draw the same in one direction and when the branch 7 of the clothes line passes through the frames 1 that carry the grooved wheels 3, the portion thereof connected with the clothes line proper will assume the angular positions illustrated by Figure 3 of the drawings and thereby freely travel through the frames, 70 while the laundered articles, or rather the securing pins therefor will travel outwardly over and to the opposite sides of the frame and to the opposite sides of the grooved wheels or pulleys 3. The connecting elements 75 8 are, of course, of a length to permit of the looping of the clothes line section 7 when the main clothes line is drawn through the grooved wheels or pulleys.

The simplicity of the invention and the 80 advantages thereof will, it is thought, be perfectly apparent so that further detailed description is not necessary, it being obvious that both sides of the auxiliary or depending clothes line 7 may be filled with laundry 85 and that the device as a whole may be brought along either of the sides of the frames and, of course, the grooved or pulley wheels 3.

As disclosed by Figure 5, the lateral mem- 100

bers 10 of the frame 11 in which the grooved wheel 12 is journaled carry pivots or shaft 13 upon which there are mounted small grooved wheels 14 that engage with the periphery of the wheel 12 to hold the cable, chain or line 15 in the groove of said wheel 12. This construction is especially designed for use when lines, similar to those previously described, but which may be formed of either hemp or chain links, are employed, and which lines are designed to support thereon breeches buoys and serve as the life line that connects a wrecked ship with the life saving workers at shore as well as supporting other cables thereon such as are used for excavating, tunnelling, subways, etc., or when used in connection with endless cables on water merry-go-rounds, etc.

The improvement is not only designed as a clothes line but is especially adapted for use in coaling ships at sea and for other uses. When employed for other purposes the length of these lines may vary, especially when the device is employed for coaling purposes, and whereby to compensate for rolling and rocking of the colliers and the vessel receiving the coal.

Having described the invention, I claim:

In a device for the purpose set forth, two oppositely disposed supporting frames carrying grooved wheels, each of said frames having its overlying members of T-shape formation with the arms of the T extending in the same direction, elements connecting the ends of the said overlying members of each frame, an endless clothes line trained around the grooved wheels, an auxiliary clothes line having its ends secured to the clothes line, spaced short flexible elements connecting the auxiliary clothes line with the endless clothes line, whereby clothes supported on the auxiliary clothes line will thru the medium of the flexing of the ends of said auxiliary clothes line and likewise of the flexing of the short strands be held from entering the frames when the endless clothes line is moved around the grooved wheels.

In testimony whereof I affix my signature.
HARRY A. MARRABLE.
